HOLLOW TRIP CASING SPEAR

Frank J. Hinderliter, Tulsa, Okla.

Application March 30, 1932, Serial No. 601,951

3 Claims. (Cl. 294—96)

This invention relates to fishing tools and will be described as embodied in an improved tool adapted for removing cylindrical objects from a deep well such for example as a drill pipe or 5 a drill casing and the like.

An object of the present invention is the provision of an improved fishing tool of the type above identified which is adapted to be lowered into a well and inserted into a pipe or well casing for lifting the same from the well.

Another object is the provision of such a tool including means for locating and passing into a pipe or casing to be lifted, and means associated therewith for forming a seal between the tool and pipe to facilitate the circulation of pressure fluid through the pipe.

A further object is the provision of such a tool incorporating means for causing the automatic gripping of the pipe by the tool and automatic release of the same upon vertical and rotary movement of the tool.

Other objects and advantages of this invention will become apparent from the following detailed description with reference to the accompanying drawings in which:

Figure 1 is an elevational view of a fishing tool incorporating my invention;

Figure 2 is a fragmentary elevation of a part of the tool shown in Figure 1 with portions broken away to more clearly show the construction thereof;

Figure 3 is a horizontal section taken on the line III—III of Figure 2;

Figure 4 is a horizontal section taken on the line IV—IV of Figure 1;

Figure 5 is a vertical sectional view substantially on the axis of the tool disclosed in Figure 1 and showing it about to be inserted in a pipe or casing to be lifted;

Figure 6 is a view similar to Figure 5 showing the tool inserted in the casing to be lifted with the clutch means and the sealing member adjacent the head of the tool engaging the inner surface of the casing.

The improved fishing tool as herein disclosed comprises a body 3 which is hollow having a substantially cylindrical bore 4 therein through which water or the like may be forced under pressure to aid in loosening the casing or drill pipe so that it may be more readily lifted.

The body 3 is provided adjacent its upper end with threads 5 which have engagement with threads 6 on the lower end of a cylindrical supporting element 7 which is also hollow. The upper end of the supporting element 7 is provided with an enlarged bore and internal threads 8 engaging the external threads on the lower end 9 of an actuating pipe 11.

The lower end of the body 3 has formed integral therewith a head 12 which has relatively

thick walls 13 for encountering various elements as it is being lowered into a well and to withstand wear and strain while protecting the remainder of the tool. The lower end of the head 12 is tapered at 14 to facilitate the location of the casing or pipe 17 to be lifted and to facilitate the entrance of the tool into such a pipe. Adjacent the upper edge of the head is provided a gasket or annular sealing member 15 preferably formed of rubber or the like to form a seal between the 10 tool and the inner surface of the pipe or casing 17 as shown in Figure 6. The sealing member 15 is interposed between two metal rings 18 and 19 which may be split rings, as shown in Figures 1 and 4, in order that they may be pressed into 15 position. The ring 18 is seated upon the shoulder 21 and the ring 19 engages beneath the shoulder 22 as best illustrated in Figures 5 and 6.

Between the upper cylindrical portion of the body 3 and the head 12, the body is provided with an outwardly tapering portion 26, the outer surface of which forms an annular cam 27 which cooperates with the internal cam surface 28 on the lower portion of the clutch or wedge member 29 for the purpose of expanding the clutch member when it is lowered relative to the body caused by friction engagement of the teeth 31 with a pipe or the like 17 as illustrated in Figure 6. The clutch member includes a shank portion 32 having a shoulder 33 on which is seated a coil spring 34. The upper edge of the coil spring 34 normally presses against the lower end of the supporting element 7 and as thus interposed between the supporting member 7 and the clutch member, it tends to force the clutch member 35 downwardly which downward movement is however restrained by the coaction of the cam surfaces 27 and 28, but the clutch member when aided by frictional force from the pipe 17 does become forced downwardly over the cam surface 27 and 40 firmly engages the inner surface of the pipe 17 sufficiently that the pipe 17 may be withdrawn from a deep well in which it may be situated.

In case it is found to be impossible to lift the casing or pipe 17 after the clutch has been firmly 45 engaged therewith it may be desirable to withdraw the fishing tool from the pipe. For such a purpose I have provided cooperating means on the body 3 and on the clutch whereby the clutch may be automatically released from the casing 50 17 upon proper manipulation of the body relative to the clutch.

Referring particularly to Figures 1, 2, and 3 of the drawings, the body 3 is provided with bores 41 in which radially extending pins 42 have 55 threaded engagement to hold them rigidly in position. The clutch member 29 is provided with axially extending bayonet slots 43 in which the pin 42 extends. The bayonet slots 43 include offset slots 45 into which the pins 42 may be rotated. 60

When the pins 42 are in the position shown in Figure 2 lifting of the body causes the clutch member to be released from the casing 17 and permits the fishing tool as a whole to be withdrawn from the casing and lifted from the well.

The upper end or shank of the clutch member has an enlarged portion 51 on the outer surface of which is fixed a slip ring or band 52 of relatively hard metal to resist wear occasioned by friction along the surface of the well. The ring 52 is held from vertical movement relative to the clutch member by means of a flat spring 53 formed into a ring and fitted into a groove on the inner surface of the ring. To prevent rotational movement of the slip ring 52 relative to the clutch member, locking pins 55 are provided which engage in apertures 57 in the portions 51 and engage in vertical grooves 56 in the inner surface of the ring 52. This ring 52 is also useful in causing the clutch member to rotate relative to the body by reason of frictional engagement of the ring 52 with the sides of the well when the body is rotated, to facilitate engagement or disengagement of the pins 42 from the side slots 45 in the clutch member as above described.

In the operation of my invention the tool is first lowered into a well by a series of pipes 11. As the tool approaches the casing to be lifted as shown in Figure 5, the sealing member 15 is somewhat expanded. The tapered portion of the head 12 guides the tool into the casing 17 and protects the sealing member 15 from injury. It also protects the clutch member from damage as it is lowered through the well and into the casing 17 in the manner shown in Figure 6. With the tool in this position, a slight lifting of the body will cause the clutch member 29 to firmly grip the inner surface of the casing 17 such that upon further upward movement of the body, the casing 17 is drawn vertically from the well.

In case great difficulty is encountered in lifting the casing from the well after the tool has been properly set, fluid under pressure may be forced downwardly through the hollow body 3 and through the casing into the bottom of the well to loosen or displace earth that may be crowding the casing. The sealing ring 15 disposed adjacent the head 12 prevents the escape of fluid between the casing and the tool thereby avoiding loss of pressure. This arrangement makes the introduction of water or the like under pressure very practical in loosening the casing.

Sometimes it so happens that regardless of the amount of fluid and pressure applied, it is impossible to remove the casing from the well and in such case it is obviously desirable to remove the tool from the casing. In order to accomplish the removal of the tool from the casing it is first necessary to release the clutch 29 from its gripping engagement with the inner surface of the casing 17. To effect such a release, the tool is first forced downwardly as far as it will go and then rotated in a direction to cause the pins 42 to engage in the side slots 45 of the bayonet slots 43 into the position shown in Figure 2. When in this position the lifting of the body causes the pins 42 to lift the clutch member 29 and prevent it moving downwardly and expanding by reason of the cam face 27 on the lower portion of the body. As the clutch is lifted with the body the gripping engagement with the inner surface of

the casing 17 becomes released and the tool may be then withdrawn from the well.

Although only a preferred form of this invention has been described herein, it will be appreciated by those skilled in the art that the device herein disclosed is susceptible of various modifications, and there is no intention to limit the patent to be granted hereon except as required by the prior art.

I claim as my invention:

1. In a tool of the class described in combination, a tubular body, a substantially cylindrical clutch member disposed on the outside of said body and adapted for gripping engagement with a pipe, said clutch member including teeth on the outer surface of the lower portion, and a shank portion adjacent the upper end of said body, a slip band surrounding the upper portion of said shank, means for locking said band to said shank, said body including a tapered portion forming a cam engageable with said clutch member, to expand the same upon relative upward movement of said body, and means carried by said body engageable directly with the shank of said clutch member for automatically releasing said clutch member from a pipe upon upward movement of the body.

2. In a tool of the class described in combination, a tubular body, a substantially cylindrical clutch member disposed on the outside of said body and adapted for gripping engagement with a pipe, said clutch member including teeth on the outer surface of the lower portion, and a shank portion adjacent the upper end of said body, a slip band surrounding the upper portion of said shank, means for locking said band to said shank including a retractable ring and a radially extending pin carried by the shank, said body including a tapered portion forming a cam engageable with said clutch member to expand the same upon relative upward movement of said body, and means on said body engageable with the shank of said clutch member for automatically releasing said clutch member from a pipe upon upward movement of the body, said body including an enlarged head tapered at the lower end to guide said body into a pipe in a well.

3. In a tool of the class described in combination, a tubular body, a substantially cylindrical clutch member disposed on the outside of said body and adapted for gripping engagement with a pipe, said clutch member including teeth on the outer surface of the lower portion, and a shank portion adjacent the upper end of said body, a slip band surrounding the upper portion of said shank, means for locking said band to said shank against relative movement therebetween, said body including a tapered portion forming a cam engageable with said clutch member to expand the same upon relative upward movement of said body, means on said body engageable with the shank of said clutch member for automatically releasing said clutch member from a pipe upon upward movement of the body, said body including an enlarged head tapered at the lower end to guide said body into a pipe in a well, an annular resilient sealing member fixed on said body adjacent said head, and being of larger external diameter than the head for sealingly engaging a pipe in which it may be positioned.

FRANK J. HINDERLITER.
